UNITED STATES PATENT OFFICE.

FRANK Y. BARBA, OF ASTORIA, NEW YORK.

ATTACHMENT FOR TYPOGRAPHICAL MACHINES.

Application filed May 3, 1926. Serial No. 106,182.

This invention relates to protective devices for use on linotype machines, the particular object being the provision of means for preventing the spattering of molten metal when a blank or typographed slug is cast, in the event that the type matrices and spacebands in the matrix holder or vise jaws are not properly held. This spattering of the molten metal is dangerous to the operator and occurs principally when the matrices are loosely held as when they become worn or when the line is improperly justified, when the metal is too hot, when spacebands slip off the jaws, and when small fragments of metal adhere to a matrix or spaceband thereby causing the occurrence of an opening therebetween.

Another object of the invention is the provision of means which will make it unnecessary for the operator to manually hold the vise jaws together during the casting of blank slugs.

To the attainment of these and other objects hereinafter appearing, I have provided certain new and useful protective mechanism which comprises, generally, a movable shield which in the form illustrated is pivoted to rotate into and out of protective position by an actuator or arm attached to a movable part of the mechanism whereby it is properly timed with reference to the casting operation or ejection of the molten metal.

One embodiment of the invention is illustrated in the accompanying drawings, in which:

Fig. 1 is a side elevation, partly in section, of a linotype machine in position for casting a type slug, the shield being shown in protective position covering the mold, vise jaws and matrices.

Fig. 2 is a side elevation, partly in section showing the casting parts of a linotype machine the lead pot being retracted out of casting position and the shield held out of protective position and

Fig. 3 is a perspective view of a part of the front of a linotype machine showing the shield in protective position.

Throughout the drawings like reference numerals indicate like parts.

The linotype machine herein illustrated consists, briefly, of a metal pot 1 having a spout 2 through which the molten metal is ejected into the slot comprising the mold 3, the ejection of the molten metal being

accomplished by a plunger 4 the downward movement of which occurs after the pot has been brought into casting position. The pot is supported to swing toward and from the mold by means of the legs 5 pivoted at 6 on the main frame 7.

Intermediate the pot and the first elevator, generally indicated as 11, is the rotatable drum 8 through which the molds 3, 3 extend transversely. The drum is carried on the shaft 9, and contains water-compartments 10, 10, for cooling.

The elevator mechanism holding the matrices during the casting operation and for transporting them after the casting operation comprises a frame 12 and the channelled rails 13, the latter being shown as carrying a matrix 14 and a space bar 15. The justification mechanism is indicated generally by 16. It is understood by those familiar with machines of this character that the matrices, after being brought into the position shown in Fig. 1, by the elevator, are clamped between the usual vise jaws which are set to operate at certain given distances apart according to the length of the line to be cast and that the spacebands located between the matrices are moved vertically to justify the line by positively separating the matrices. When blank slugs are to be cast, the operator closes the jaws of the vise together by moving them laterally to contact with each other.

The protective device or squirt cap arranged in accordance with my invention is indicated by 17 and is arranged to cover the holder in which the matrices are supported during the casting operation. The size of the device is preferably sufficiently great so as to also cover the joint formed between the edges of the row of matrices and the mold, and it extends above the surface of the rails 13 a distance sufficient to permit the raising of the spacebands during justification above the upper edges of the matrices. Its purpose is to intercept any extruded metal that may be forced out between the edges of the mold and the matrices, or between adjacent matrices or spacebands and prevent such from spattering.

A convenient arrangement of the shield is the arcuate shape shown in the drawings with spaced ends so that when in protective position its forward edge is between the point of ejection of the metal and the operator and its top portion curves rearwardly

herefrom over the matrices, but spaced therefrom. By curving the shield and spacing it from the matrices, a dual end is accomplished in that any spatters which may occur will not only be directed rearwardly but also must pass through an air space before impinging against the shield. In this way the metal partially congeals before reaching the shield so that any portions which may fall back onto the matrices will not readily adhere to them.

The cap or shield 17 is pivoted at its ends, as indicated at 18, to fingers 19 depending from an overhanging portion of the frame 20, so that it may be rocked or oscillated in timed relation to the movement of the metal pot and the extruding operation and thereby cause it to be placed in the covering position in advance of the molding or casting of the type slug. One method of effecting such movement of the cap is to connect it directly with the pot as by an arm preferably made in two parts, as 21 and 22, which are capable of relative longitudinal adjustment. One part of the arm, as 21, is then pivoted to a lug 23 on the pot, while the other part, 22, is journaled to the cap, as to one end thereof.

On the elevator between the rails 13, which form the matrix holder, there is normally an open space on the end adjacent the operator, through which molten metal in the form of squirts or spatters may reach the operator and means are preferably provided for closing the space simultaneous with the operation of the cap or shield 17 into protective position. To accomplish this, I provide on the end of the shield 17 a slotted drop-plate 24 adapted to slide on a threaded stud 25 on the shield, so that when the shield is rotated out of the protective or covering position to permit the vertical movement of the elevator, the weight of the draw-plate together with the upper edge of the elevator in its upward movement will cause the plate to drop back out of the path of the elevator by sliding in the slot on the stud 25. In order to insure the return of the drop-plate 24, to the proper position for subsequently closing the space between the rails 13, there is provided a stop, as the pin 27, against which the drop-plate will rest.

Blank slugs are quite frequently cast in the molds of the linotype machine by bringing together the vise jaws and thereby closing any given mold, the operation being performed when no matrices are in position in front of the mold. The vise jaws may be closed either manually or by moving a lever 26 provided for this purpose, the former operation however, being preferable since motion of the lever 26 does not insure a firm contact between the vise jaws and therefore does not prevent squirts resulting from an opening between the vise jaws being present.

Since the casting of a blank slug is but a

momentary operation, the operator usually safeguards himself by manually holding the vise jaws together. This method of casting a blank slug, however, requires that the operator remove his hand from the jaws before the elevator arises and therefore endangers his hand. Hence, in casting blank slugs with a machine on which my device has been provided, the operation is especially safer and easier for the operator, since the lever 26 may be employed without placing the operator in danger of squirts.

In accordance with the provisions of the patent statutes the principle of the invention has been described, and illustrated by the portrayal of a structure which in practice has proved to be a satisfactory embodiment thereof, but it is desired to have it understood that the structure shown is merely illustrative, and that the invention may be carried out in other ways.

The invention having been described, what is claimed as new and desired to be secured by Letters Patent is as follows:

1. The combination with a typographical machine comprising a holder for matrices, a mold cooperating therewith and means for forcing molten metal into the mold, of a device arranged to extend over the joint formed between said holder and mold and means for actuating it into operative position in advance of the casting operation.

2. The combination with a typographical machine comprising a holder for type matrices, a mold cooperating therewith and means for forcing molten metal into the mold in contact with matrices in the holder, of a shield movable into and out of a position to cover the matrices in the holder and means for actuating the shield into covering position prior to the casting operation.

3. The combination with a typographical machine comprising a holder adapted to receive a plurality of vertically disposed matrices, a mold extending laterally from one side of the row of matrices in the holder, a pot for molten type metal movable into and out of register with said mold and having means for ejecting metal into the mold, of a shield pivoted to rotate into a position to cover the ends of the matrices and the joint formed between them and the mold and means for actuating the shield relatively to the metal ejecting means.

4. The combination with a typographical machine having a matrice holder, a mold, a pot for molten type metal movable into and out of engagement with the mold and having means for ejecting the metal into the mold, of a pivoted protecting member, and a connection between the latter and the pot for moving said member over the matrix holder when the pot is in casting position.

5. A squirt cap for typographical machines arcuate in shape and having end

pieces, said cap being adapted to be pivoted for oscillatory movement above the matrix holder and to cover the latter during the casting operation.

5 6. The combination with a typographical machine comprising a holder for matrices, a mold, a movable pot for molten type metal having means for ejecting said metal and means for moving said pot into and out of engagement with the mold, of a squirt cap pivoted to rotate into a position to cover the matrix holder and means for moving it into said position in advance of the ejecting operation and retracting it upon the completion of said operation.

7. The combination with a typographical machine including a pair of channeled rails forming an enclosure open at the top and adapted to hold a plurality of matrices, a mold, a pot for molten type metal movable 20 into and out of register with the mold and having means for ejecting metal into the mold, of a shield movable into and out of a position covering the enclosure, a drop-plate slidably mounted on the shield and 25 filling the end of the enclosure adjacent the operator during the ejecting operation.

This specification signed and witnessed this 30th day of April, 1926.

FRANK Y. BARBA.
